GARMENT HANGER

James K. McGhie, Croton-on-Hudson, N. Y.

Application March 14, 1950, Serial No. 149,501

14 Claims. (Cl. 223—85)

The present invention relates to apparel apparatus and more particularly to garment hangers adapted for use in suspending garments and the like from a supporting rod or line.

One of the objects of the present invention is to provide a garment hanger embodying novel hook and guard means which will effectively prevent accidental dislodgment of the hanger from the supporting rod or the line and the consequent falling of the hanger and any clothes which may be on it.

Another object of the invention is to provide a garment hanger, the novel construction of which makes it possible to remove a garment therefrom without removing the hanger from its supporting rod while at the same time having assurance that the hanger will not rock or oscillate off the rod after the garment has been removed and the hanger released by the user.

A further object is to provide a novelly constructed hanger for garments and the like which may be placed on and removed from a supporting rod or line with comparative ease but which will effectively resist accidental removal.

Still another object is to provide a hanger for garments or other articles embodying novel guard means which will prevent accidental removal of the hanger from a supporting rod or line and which are automatically operable by said rod or line when the hanger is placed thereon or removed therefrom in the usual manner by a user.

A still further object is to provide a novel form of hook and latch means which may be readily embodied in a garment hanger or the like.

Another object is to provide a garment hanger of novel construction which is substantially balanced with respect to its normal point of suspension on a supporting rod or line.

The above and further objects and novel features of the invention will more fully appear from the following detailed description when the same is read in connection with the accompanying drawings. It is to be expressly understood, however, that the drawings are for the purpose of illustration only and are not intended to define the limits of the invention, reference for this latter purpose being had primarily to the appended claims.

In the drawings, wherein like reference characters refer to like parts throughout the several views,

Fig. 1 is a side elevation view, partly in section, illustrating one type of wooden or plastic garment hanger embodying one form of the invention;

Fig. 2 is an enlarged detail sectional view taken substantially on line 2—2 of Fig. 1;

Fig. 3 is a view similar to Fig. 1 showing a wire hanger embodying the same form of the invention;

Fig. 4 is a view similar to Fig. 1, with parts broken away, showing a modified form of the invention;

Fig. 5 is a side elevation view, partly in section and with parts broken away, of another type of hanger embodying still another form of the invention; and,

Fig. 6 is an enlarged detail view, partly in section and with parts broken away, taken substantially on line 6—6 of Fig. 5.

A limited number of embodiments of the invention are illustrated in the accompanying drawings, by way of example, as being incorporated in simple forms of garment hangers of types comparable to those used extensively in homes, stores and wherever clothes are to

2

be hung. In Figs. 1 and 2, one novel form of hook and guard mechanism comprehended by the invention is shown in combination with a simple known type of curved yoke or bar 10 made of wood or other suitable material, such as plastic or metal. The hook 11 is adapted to engage a supporting rod 12 and may be made of stiff wire or the like in a very simple form that may be inexpensively executed. As shown, said hook comprises an upwardly and laterally inclined straight portion 14 and a curved or hooked portion or crown 15 that terminates in spaced relation to the yoke, thus forming an entrance for rod 12. The free end of the straight portion 14 may be secured in a drilled opening 16 in yoke 10 in any known manner such as by flattening a portion of the wire to form one or more tabs 17 that bite into the walls of opening 16 and prevent further downward movement of the wire through the yoke. The tip of the wire may be flattened as at 18 to prevent withdrawal thereof in the other direction. When the bar 10 is made of plastic or other similar materials, the end of wire 14 may be molded therein.

Novel guard or closure means are provided in combination with the above described parts for preventing accidental removal of the hanger from the supporting rod, said means being automatically operable by the rod when the hanger is used in the usual manner and of simple construction which can be inexpensively incorporated. As shown in Figs. 1 and 2, said guard means comprises a substantially rigid shank or spindle 19 which may be of the same material and mounted on bar 10 in the same manner as hook 11. Said shank preferably diverges from the straight portion 14 of the hook at the same angle relative to bar 10 and in direct alignment with the end of hook portion 15. The space or entrance for rod 12 between the free end of hook 15 and the end of spindle 19 is substantially closed or bridged by a rigid bar or closure member 20 which may likewise be made of stiff wire or the like. The hook, shank and closure member may in fact be installed on yoke 10 as a unitary loop of stiff wire and thereafter cut in two places to form the three elements 11, 19 and 20 and hence the entrance for rod 12.

The hook entrance closing member 20 is mounted on spindle 19 in a novel manner for substantially universal pivotal movement relative thereto by means of a stiff coil spring 21. The latter is constructed to surround and tightly grip the adjacent end portions of closure member or bar 20 and spindle 19 and to function as a yielding support for the closure member in longitudinal axial alignment with said spindle and the free end of hook 15. The extreme end turns of spring 21 may be somewhat reduced to snap into grooves 22 and 23 in spindle 19 and member 20, respectively, and thereby provide additional assurance against any disengagement of the spring from either of these parts. Spring 21 is preferably closely wound and made of stiff spring wire so that it will give sufficient rigidity to closure means 20, 21 for preventing accidental removal of the hanger from rod 12 or similar support, such as a clothes line.

When it is desired to place the hanger on rod 12 it is only necessary to elevate the same to the plane indicated by the dotted line position of Fig. 1, with closure member 20 engaging rod 12, and to then move the hanger to the right and downwardly (as viewed in Fig. 1) in the customary manner. Spring 21 will yield under sufficient pressure, which need not be great, and permit guard or closure member 20 to move to dotted line position B and permit the hook to operably engage rod 12. When it is desired to remove the hanger from the supporting rod, it is only necessary to lift it off in the usual manner, applying only sufficient additional effort in a horizontal or lateral direction to flex the guard or closure means 20, 21 to dotted line position C. If a garment is removed from the hanger without removing the latter from rod 12, the guard means will effectively prevent the hanger from falling off the rod when it is released by the user to swing or oscillate in the usual manner.

The embodiment of Fig. 3 incorporates the same form of the invention as above described but in combination with a wire type hanger. A single stiff wire is bent to form yoke consisting of a cross bar 24 and inclined shoulder bars 25—25, a hook 26 and closure shank or spindle 27. The guard or closure bar 20 is mounted

on spindle 27 by means of spring 21 in the same manner as above described in connection with the embodiment of Fig. 1. In this construction it will be noted that the hanger yoke, hook and spindle are integral parts. In a hanger of the molded plastic type either or both the hook and the closure supporting spindle may be molded integrally with the garment engaging part or yoke of the hanger.

The embodiment illustrated in Fig. 4 is constructed and operates in the same manner as the structure of Fig. 1, except that the guard or closure means for the hook entrance embodies a different form of spring for supporting the closure member. As shown, the supporting spring 28 is in the form of a round or flat leaf spring with its ends secured to and preferably embedded in the adjacent end of members 19 and 20. The straight resilient member 28 functions in the same manner and for the same purpose as the spring 21.

In the embodiment of Figs. 5 and 6 there is disclosed a form of the invention which is especially adapted for the heavier, more sturdy type hangers of familiar design. As shown, the yoke of the hanger comprises two inclined shoulder bars 29, 29 joined by a relatively bulky central portion 30. The latter is provided with a recess 31 in which a metallic container or liner 32 is suitably secured, such as by one or more rivets 33. The lower end of a wire hook 34 is soldered or otherwise suitably secured to the liner 32 at one end of the recess and a leaf spring 35 having a free horizontal arm in the central portion of the liner is secured to the bottom of the latter and if desired, to the wire of hook 34. Mounted pivotally on a transverse shaft 36 above the horizontal arm of spring 35 is a closure member 37 for the entrance to hook 34. Member 37 comprises a hub 38, a rigid arm 39 extending upwardly from the hub to a point adjacent the free end of hook 34, and a rigid arm 40 which extends laterally from arm 39, the latter being preferably curved in such a manner as to form a symmetrical loop with hook 34. The adjacent ends of hook 34 and closure bar 39 are preferably bevelled and extend into overlapping relation to limit pivotal movement of bar 39 in a counterclockwise direction, as viewed in the drawings. Hub 38 has two flat surfaces on the periphery thereof adapted to be engaged by the horizontal arm of spring 35 when closure member 37 is in hook closing and hook opening positions. The spring is thus effective to yieldably hold the closure member in either open or closed position, the open position thereof being indicated in dotted lines (Fig. 5).

In order to remove the hanger of Fig. 5 from supporting rod 12 it is only necessary to lift the hanger slightly, engage closure arm 39 with the side of rod 12 and then shift the hanger to the left, all in the usual manner of removing a hanger from a support. The outward pressure applied to the hook closing member through the reaction of rod 12 will cause it to pivot about shaft 36 and against the pressure of spring 35 to the dotted line or open position. In this position spring 35 will engage the other flat surface on the hub to yieldably hold member 37 against return to closed position. The lateral arm 40 extends upwardly at an angle when member 37 is in open position so that as the hanger is replaced on rod 12, the latter will engage arm 40, and the member 37 will be returned to entrance closing position in response to the necessary replacement movement of the hanger.

In the embodiments of Figs. 1 and 3, the adjacent ends of closure members 20 and shanks 19 and 27, respectively, within the coils of spring 21 may be comparatively flat and reasonably close together so that they will coact with each other to damp the vibrations of spring 21 when the closure member is released from open positions B and C (Fig. 1). This construction is best illustrated in Fig. 2 wherein the axial distance between the ends of members 19 and 20 is shown as being less than the pitch of the coil spring. If desired, of course, the ends of these members may butt against each other when the member 20 is in entrance closing position, or the ends thereof may be rounded or shaped to coact like a ball and socket joint to thereby avoid any interference with the action of the spring itself. It will be obvious that the lower ends of hook 26 and shank 27 adjacent yoke 25 in the embodiment of Fig. 3 may be laterally spaced as are the corresponding parts in the embodiment of Fig. 1. In one manner of effecting this result, the adjacent ends of bars 25 could be twisted together in a horizontal plane for the desired

distance to separate the elements in question. In this form of hanger, the distance between the yoke and the crown of the hook could be reduced to a minimum.

There is thus provided a garment hanger of simplified and inexpensive construction and of pleasing appearance embodying novel means which will effectively prevent the hanger from falling to the floor by accident. One of the most prevalent causes of damage to hangers is thus eliminated as is also one of the greatest sources of dirt and lint transferred from hangers to clothing. A great deal of unnecessary stooping by the user to pick up hangers is also avoided.

Although only a limited number of embodiments of the invention are illustrated in the drawing and described in detail in the foregoing specification, it is to be expressly understood that the invention is not limited thereto but that various changes may be made in the design and arrangement of parts illustrated as well as in the particular materials suggested without departing from the spirit and scope of the invention, as will now be apparent to those skilled in the art.

What is claimed is:

1. A garment hanger comprising a yoke, a hook secured at one end to the central portion of the yoke and terminating at its other end in spaced relation to the yoke to form an entrance for a supporting rod operatively engageable by the hook, and closure means for said entrance including a rigid spindle rigidly secured to said yoke and extending into said entrance, resilient means mounted on the free end of said spindle and a rigid bar mounted on the free end of said resilient means and extending, when said resilient means is unbiased, into proximity with the free end of said hook, said spindle, resilient means and bar being an assembly of separate parts which in assembled relation are shorter in overall length than the distance across said entrance to permit movement of the bar to-and-fro passed said free end of the hook in the plane of the latter without engaging the same, said to-and-fro movement being yieldably resisted by said resilient means.

2. A garment hanger as defined in claim 1 wherein the resilient means is constituted by a straight leaf spring secured to adjacent ends of said spindle and bar.

3. A garment hanger as defined in claim 1 wherein the hook and spindle are formed integrally with the yoke.

4. A garment hanger as defined in claim 1 wherein the yoke, hook and spindle are formed from a single piece of stiff wire.

5. A garment hanger comprising a yoke, a hook secured at one end to the yoke and terminating at its other end in spaced relation to the yoke to form an entrance for a supporting rod which is operatively engageable by the hook, and closure means for said entrance including a spindle secured to said yoke and extending into said entrance and elongated flexible means extending between the free ends of said spindle and hook, said flexible means including a coil spring mounted on and longitudinally coaxial with said spindle, said spring having a plurality of turns at one end thereof surrounding and gripping the free end of said spindle.

6. A garment hanger as defined in claim 5 wherein said flexible means includes a rigid bar supported by the coil spring and extending into proximity with the free end of the hook, said spring having a plurality of turns surrounding and gripping an end portion of said bar.

7. A garment hanger comprising a yoke, a hook having one end thereof secured to said yoke and terminating at the free end thereof in spaced relation to said yoke for forming an entrance to the hook for the passage of a supporting bar adapted to be operatively engaged by the hook, a rigid closure member pivotally mounted on said yoke and extending across said entrance into proximity with the free end of the hook when the member is in position to close said entrance, and resilient means engageable with said member for yieldably holding the same in entrance closing position, said closure member being engageable by the supporting rod for movement to entrance opening position when the hanger is removed from the rod.

8. A garment hanger as defined in claim 7 wherein said closure member has a laterally extending arm engageable by said rod for pivoting the closure member to entrance closing position while the hook is being operatively engaged with said rod.

9. A garment hanger as defined in claim 7 wherein said resilient means engages different surfaces of said closure member to yieldably hold the latter in open and closed positions.

10. A garment hanger comprising a yoke, a hook having one end formed integrally with the central portion of the yoke and terminating at its other end in spaced relation to the yoke to form an entrance for a supporting rod operatively engageable by the hook, and closure means for said entrance including a rigid spindle formed integrally with said yoke and extending into said entrance, resilient means mounted on the free end of said spindle and a rigid bar mounted on the free end of said resilient means and extending into proximity with the free end of said hook.

11. A garment hanger comprising a yoke, a hook secured at one end to the central portion of the yoke and terminating at its other end in spaced relation to the yoke to form an entrance for a supporting rod operatively engageable by the hook, and closure means for said entrance including a rigid spindle secured to said yoke and extending into said entrance, said yoke, hook and spindle being formed from a single piece of stiff wire, resilient means mounted on the free end of said spindle and a rigid bar mounted on the free end of said resilient means and extending into proximity with the free end of said hook.

12. A garment hanger comprising a yoke, a hook secured at one end to the central portion of the yoke and terminating at its other end in spaced relation to the yoke to form an entrance for a supporting rod operatively engageable by the hook, and closure means for said entrance including a rigid spindle secured to said yoke and extending into said entrance, resilient means mounted on the free end of said spindle, said resilient means being separable from and longitudinally coaxial with said spindle, and a rigid bar separable from and mounted on the free end of said resilient means in longitudinal coaxial relation thereto and extending into proximity with but short of the free end of said hook.

13. A garment hanger comprising a yoke, a hook se-

cured at one end to the central portion of the yoke and terminating at its other end in spaced relation to the yoke to form an entrance for a supporting rod operatively engageable by the hook, and closure means for said entrance including a rigid spindle rigidly secured to said yoke and extending into said entrance, resilient means mounted on the free end of said spindle and a rigid bar mounted on the free end of said resilient means and extending, when said resilient means is unbiased into proximity with the free end of said hook for movement to-and-fro, passed said free end of the hook without engaging the same, said movement being yieldably resisted by said resilient means, the latter comprising a coil spring which surrounds and grips the adjacent end portions of said spindle and bar.

14. A garment hanger comprising a yoke, a hook secured at one end of the central portion of the yoke and terminating at its other end in spaced relation to the yoke to form an entrance for a supporting rod operatively engageable by the hook, and closure means comprising an assembly of a rigid spindle, elongated resilient means and a rigid bar, said spindle, resilient means, and bar being assembled in longitudinal, coaxial relation to each other with the resilient means normally unbiased and disposed intermediate the bar and the spindle, the latter being rigidly secured to said yoke and said bar normally extending into proximity with, but short of, the free end of said hook, whereby said resilient means is free to flex and permit said bar to move to-and-fro passed the free end of said hook without interference by the latter to permit said rod to enter and be removed from said hook.
